Primary Examiner — Melanie Pellegrini

(57) **CLAIM**

The ornamental design for a finger ring as shown and described.

DESCRIPTION

1. Finger ring

1.1: Front

1.2: Back

1.3: Left

1.4: Right

1.5: Bottom

1.6: Top

1.7: Perspective

The design consists of a finger ring with two parallel rows of cubes; a row of diamonds is placed between the parallel rows of cubes; all the angles on the sides of the faces of the cubes are cut at 45 degrees.
